CEMENT MIXER

Robert Gilmore Le Tourneau, Peoria, Ill., assignor to R. G. Le Tourneau, Inc., Stockton, Calif., a corporation of California

Application October 29, 1946, Serial No. 706,470

8 Claims. (Cl. 259—161)

1

This invention relates generally to an improved cement mixer, and in particular is directed to a cement mixer of portable or transit-mix type; i. e. the implement is self-propelled, and is operative to mix the cement en route between the batching plant and the place of pouring.

One object of the invention is to provide a portable cement mixer whose novel design is advantageous to the end that the implement has a large capacity; a very effective mixing action; and is capable of discharging the mix, at a regulated delivery rate, adjacent the ground, or at an elevated point beyond that capable of presently used portable cement mixers. Concrete structures of a story in height can be easily poured without the use of conventional elevators, wheelbarrow handling of the mix, etc.

Another object of the invention is to provide a portable cement mixer which includes a greatly elongated mixing and feeding cylinder projecting to the rear of the implement, and the cylinder being supported for adjustment to vary the inclination thereof whereby low or high discharge points are possible; such adjustment being effected by a power actuated swing frame in which the cylinder is mounted.

A further object of the invention is to impart the necessary rotation to the mixing and feeding cylinder by means of a reversible power unit direct connected to one end of the cylinder and movable with the swing frame which is employed to alter the inclination of said cylinder as above; such power unit including an electric motor driving through a reduction gear box.

An additional object of the invention is to provide a power control mechanism wherein control of the mixing cylinder, during transport and discharging operations, is controlled by the operator from his station on the tractor.

A further object of the invention is to produce a practical device and one which will be exceedingly effective for the purpose for which it is designed.

These objects are accomplished by means of such structure and relative arrangement of parts as will fully appear by a perusal of the following specification and claims.

In the drawings:

Figure 1 is a side elevation of the portable cement mixer with the cylinder lowered for transport or low point discharge.

Figure 2 is a similar view but with the cylinder (partly broken away) elevated for high point discharge.

Figure 3 is a plan view of the implement.

2

Figure 4 is a rear end view of the cylinder as mounted in the swing frame.

Figure 5 is an enlarged fragmentary sectional elevation of the power unit and its connection with the forward end of the cylinder.

Referring now more particularly to the characters of reference on the drawings, the portable cement mixer comprises a main frame 1 of general yoke type including side beams 2 and a front cross beam 3 having a central neck 4 adapted to attach to a coupling and power steering unit 5 on a tractor 6 at the rear. The frame 1 is supported at the rear by wheels 7 whose mount is secured to the side beams 2.

15 A greatly elongated mixing and feeding cylinder 8 is disposed lengthwise of the implement above the main frame 1 and projects rearwardly to a point some distance back of the frame; said cylinder tapering toward its rear end from an intermediate point as shown, and said rear end remains open.

20 A swing frame 9, of open construction, straddles the forward half of the cylinder 8 from above and the latter is rotatably mounted and driven in said swing frame as follows:

25 At its forward end the swing frame includes a mounting ring 10 disposed with its axis lengthwise of the implement and directly ahead of the front end of the cylinder, which is dished, as at 11. The ring 10 is concentric to the cylinder axis.

30 A reversible electric actuator 12 including a gear box 13 and a rearwardly projecting drive spindle 14 is mounted by a circular attachment plate 15 in the ring 10. The actuator is hooded as at 16.

35 The spindle 14 passes through an end bearing 17 of the actuator, and then engages through a double ended hub 18 supported concentrically in the dished end 11 of the cylinder by a removable circular attachment flange 19. The outer end of spindle 14 has a neck 20 spline-engaged in driving relation to hub 18 and consequently the cylinder 8. A locking collar or nut 21 prevents separation of the spindle 14 and hub 18.

40 In the above manner the front end of cylinder 8 is supported and driven by the electric actuator; there being an intermediate support for the cylinder as follows:

45 50 At its rear end the swing frame 9 includes a cradle member 22 having spaced rollers 23 therein which are engaged by and support a bearing ring 24 on the cylinder intermediate its ends.

The cylinder is thus rotary mounted in the 55 swing frame, and the latter is pivotally suspended

adjacent its front end and at the top, as at 25, from an upstanding rigid post assembly 26 on the main frame 1, whereby the swing frame can be swung about said pivotal axis to selectively dispose the cylinder in a lowered (Fig. 1) or elevated (Fig. 2) position.

The mechanism for so moving the swing frame 9 comprises:

An electric winch 27 is mounted on the cross beam at one end thereof, and a cable 28 leads from the winch drum 29 at a downward and rearward incline along one side of the main frame 1. Alongside the corresponding side beam 2, the cable is reeved, as a block and tackle system 30, between sheave blocks 31 and 32 secured to said side beam and a forwardly disposed low point on the swing frame 9 respectively.

From the block and tackle cable system 30, the cable passes across the implement, being guided by direction changing sheaves 33, and on the opposite side is reeved between sheave blocks 34 and 35 to form another like block and tackle cable system 36 coupled between the main frame and swing frame and working in unison with system 30 when the cable 28 is actuated. Upon operation of winch 27 to shorten cable 28, including block and tackle cable systems 30 and 36, the swing frame is swung upwardly about pivot 25 as the sheave blocks 32 and 35 move rearwardly, thus elevating the cylinder 8 for high point discharge as in Fig. 2. The winch 27 has an automatic holding brake operative to maintain the cylinder 8 in a selected position of elevation.

The forward portion of the cylinder 8 is fitted with a man-hole unit 37 including a removable cover as shown to permit of entry of the dry mix and water into such cylinder.

Within the same the cylinder 8 is fitted with a pair of longitudinally extending helical mixing and feeding blades or vanes 38 which are fixed to and project radially inwardly from the cylinder wall; corresponding convolutions of such blades being 180 degrees apart, and such blades decreasing in width radially of the cylinder to compensate for the taper of the latter.

The electric actuator 12 and winch 27 are interposed in control circuits (not shown), switch-regulated by the tractor operator from his station; such circuits being energized by a generator on and driven by the tractor.

Operation

When the implement is in use, the cylinder 8 is initially in lowered position, and the dry mix and water are introduced into such cylinder, at the batching plant, through the manhole unit 37.

Thereafter, en route to the pouring point, the reversible electric actuator 12 is run at a relatively low speed in a direction such that the helical blades 38 feed the mix toward the closed forward end of the cylinder, thus assuring proper mixing without spillage from the open rear end. On up-grades spillage is prevented by adjusting the cylinder to a proportionate incline.

At the pouring point the cylinder is elevated to the extent necessary to deliver directly into the forms, and then the cylinder is rotated in a reverse direction and at greater speed causing the mix to feed from the open rear end of said cylinder.

The power steering unit 5 permits the operator to effectively maneuver the implement during a pouring operation.

The described portable cement mixer provides an implement having large capacity, effective mixing en route, and selective point discharge of the mix directly over the forms; this latter advantage accruing from the relatively great projection and vertical adjustability of the cylinder 8.

From the foregoing description it will be readily seen that there has been produced such a device 10 as substantially fulfills the objects of the invention as set forth herein.

While this specification sets forth in detail the present and preferred construction of the device, still in practice such deviations from such detail 15 may be resorted to as do not form a departure from the spirit of the invention, as defined by the appended claims.

Having thus described the invention, the following is claimed as new and useful and upon 20 which Letters Patent is desired:

1. A cement mixer comprising a main frame supported for movement from place to place, an elongated mixing and feeding cylinder disposed lengthwise of the main frame and projecting to 25 the rear thereof, the cylinder being arranged to discharge from its rear end, means mounting the cylinder in connection with the main frame for adjustment between a generally horizontal position and an upward and rearward incline whereby to elevate said discharge end, the cylinder being rotatable in its mount, and power means operative to rotate the cylinder in any position of adjustment thereof; said mounting means for the cylinder being a pivotally mounted swing frame 30 including a depending frame portion, a block and tackle cable system connected between said frame portion and a rearward point on the main frame, and a power winch to actuate said cable system, shortening of the latter causing swinging of the 35 swing frame in a direction to incline the cylinder.

2. A cement mixer comprising a main frame supported for movement from place to place, an elongated mixing and feeding cylinder disposed lengthwise of the main frame and projecting to 40 the rear thereof, the cylinder being arranged to discharge from its rear end, a swing frame in which the cylinder is rotatably mounted, power means on the swing frame in driving relation to the cylinder, means pivotally suspending the swing frame on the main frame for swinging in a longitudinal vertical plane to adjust the cylinder between a generally horizontal position and an upward and rearward incline whereby to elevate said discharge end, and power actuated 45 means to adjust said swing frame; said last named means being a block and tackle cable system connected between the main frame and swing frame, and a power winch operatively connected to said block and tackle system.

3. A cement mixer comprising a main frame supported for movement from place to place, an elongated mixing and feeding cylinder disposed lengthwise of the main frame and projecting to 50 the rear thereof, the cylinder being arranged to discharge from its rear end, a swing frame in which the cylinder is rotatably mounted, power means on the swing frame in driving relation to the cylinder, means pivotally suspending the swing frame on the main frame for swinging in a longitudinal vertical plane to adjust the cylinder between a generally horizontal position and an upward and rearward incline whereby to elevate 55 said discharge end, and power actuated means to adjust said swing frame; said last named means being a pair of block and tackle cable systems.

disposed on opposite sides of the main frame and connected between the latter and forward depending members included in the swing frame, and a power winch operative to cause simultaneous actuation of said cable systems.

4. In a cement mixer, a rotary cylinder, an actuator unit beyond one end of the cylinder including a driven spindle projecting toward said end, a double ended hub mounted axially on said end of the cylinder, the spindle projecting in supported and guided relation through the hub and being splined to one end thereof, and a retaining member on the spindle bearing against the outside of said one end of the hub.

5. A cement mixer comprising a substantially horizontally disposed supporting main frame, an upstanding substantially vertical post assembly mounted on the main frame adjacent one end thereof, a cradle-like swing frame lying normally in a substantially horizontal position and having the upper corner of one end thereof pivoted to the upper end of the post assembly and the lower corner of said one end of the swing frame being disposed adjacent the sides of the main frame, a cable winch mounted on the main frame to the side of the post assembly opposite to that side on which the swing frame is disposed, a pull cable wrapped on the winch drum, a block and tackle unit which includes said cable connected between the sides of the main frame and the said lower corner of the swing frame and functioning through the operation of the winch to tilt the swing frame from its substantially horizontal position to an upwardly inclined position, and a mixing and feeding cylinder supported in said

swing frame and normally lying in a substantially horizontal position and tiltable upwardly with said swing frame.

5 6. A structure as in claim 5 including a mounting ring on the swing frame adjacent its pivoted end, a power driven spindle journaled in said ring, the adjacent end of the mixing cylinder being fixed to said spindle.

10 7. A structure as in claim 6 including a cradle member at the opposite end of the swing frame, the mixing cylinder resting intermediate its ends in said cradle.

15 8. A structure as in claim 5, including a mounting ring on the swing frame adjacent its pivoted end, a reversible electric motor supported in the mounting ring and having a projecting spindle, the mixing cylinder being fixed to said spindle.

ROBERT GILMORE LE TOURNEAU.
